BUILDING BLOCK AND WALL
CONSTRUCTIONHenry W. Haaker, Yonkers, N. Y., assignor of
one-half to Joseph Leer, Bronx, N. Y.

Application January 23, 1941, Serial No. 375,688

8 Claims. (Cl. 72—38)

This invention comprehends a building wall construction which can be erected at a considerable savings in time, labor and material, and one which is definitely moisture and frost proof.

In accordance with the present invention, the wall is composed of identically constructed building blocks designed and associated in a novel manner, to not only definitely exclude moisture from the outer face of the wall between the abutting ends of the blocks, but to also afford the wall a "weather-board" effect in appearance.

In carrying out the invention, I employ means for joining and sealing the adjacent abutting blocks of the wall construction, in addition to effectively sealing the joint therebetween on the outer face of the wall with a view of definitely excluding moisture and frost therefrom.

More specifically stated, the invention contemplates the use of a sealing key designed to completely cover the joint between adjacent blocks of the wall, and associated with said blocks in a novel and unique manner, with a view of maintaining an effective seal against the entrance of moisture at the joint between the blocks.

Another important object of the invention resides in the construction and design of the respective building blocks, whereby the sealing keys for the joints therebetween are effectively maintained in proper association with the adjacent blocks of the wall without requiring the use of auxiliary retaining means for this purpose.

The nature and advantages of the invention will be better understood when the following detail description is read in connection with the accompanying drawings, the invention residing in the construction, combination and arrangement of parts as claimed.

In the drawings forming part of this application like numerals of reference indicate similar parts in the several views and wherein:

Figure 1 is a fragmentary elevation partly in section of a wall constructed in accordance with the present invention.

Figure 2 is a top plan view of Figure 1.

Figure 3 is a sectional view on line 3—3 of Figure 1.

Figure 4 is a perspective view of one of the building blocks.

Figure 5 is a similar view of one of the sealing keys.

Referring to the drawings in detail A indicates a fragmentary portion of a wall constructed in accordance with the present invention, and composed of a plurality of identically constructed building blocks indicated generally at B. These

blocks may of course be constructed from any suitable material, finished or surfaced in any suitable manner, and also may vary in size without departing from the scope of the invention.

5 Each block is preferably of the outline illustrated in Figure 4, and if desired may be provided with any number of vertical air spaces 10 of any cross sectional contour. Depending from the front lower edge of each block is a flange 12, the purpose of which will be hereinafter described. The ends of each block are also formed with vertical channels 11 co-extensive with the height thereof. The outer face of each block at the ends thereof is further provided with 15 vertical recesses 13, the corresponding edges 14 of which are tapered or inclined as clearly illustrated. By virtue of the construction of these blocks, it is manifest that a wall possessing moistureproof qualities can be quickly and economically built, because the time, labor and cement required is reduced to a minimum.

In building a wall in accordance with the present invention, the blocks B will of course be arranged in superimposed tiers, the lowermost tier being supported upon a suitable foundation as shown. As the adjacent blocks of each tier are arranged in end to end contacting engagement, the corresponding vertical channels 11 of these blocks unitedly define passages adapted to 20 receive concrete 17 or the like by means of which the blocks are sealed and joined together. In addition to this, the corresponding tapered recesses 13 of the adjacent blocks unitedly define tapered pockets to accommodate sealing keys 15 preferably of the contour shown in Figure 5.

These sealing keys consist of substantially V-shaped plates, the opposed inclined edges 16 of which are adapted to effectively engage the correspondingly tapered edges 14 of the blocks B. 25 By virtue of this construction, it is obvious that the sealing keys 15 can be readily inserted in their respective pockets, bridging and covering the joints between the adjacent blocks of each particular tier, and thereby provide a moisture- and frostproof wall construction. It will be noted that these tapered pockets open at the upper edge of each block to permit ready insertion of the sealing keys 15 thereinto. While the sealing keys 15 are securely held in proper position in their respective pockets under their own weight, if desired they can also be subjected to a slight pressure from the blocks of the next uppermost tier, which blocks of course repose upon the adjacent ends of the sealing keys.

50 As each successive tier of the wall is built up,

the depending flanges 12 of the blocks thereof overlap the front faces of the blocks of the adjacent lower tier, including a portion of the sealing keys 15, which not only further serves to render the wall as a whole definitely moisture- and frostproof, but also affords the wall a "weather-board" effect in appearance.

Manifestly, the design and construction of the building blocks are uniform, so that they can be laid in the building of a wall by anyone with a minimum of time and effort. In other words, the construction of the wall does not require the services of an experienced artisan, while the amount of cement necessary is reduced to a minimum. The face of the wall so constructed is definitely moisture- and frostproof, while simulating a "weather-board" construction in appearance.

While it is believed that from the foregoing description the nature and advantages of the invention will be readily apparent, I desire to have it understood that I do not limit myself to what is herein illustrated or described, and that such changes may be resorted to when desired as fall within the scope of what is claimed.

What is claimed is:

1. In a wall, identically constructed building blocks disposed in superimposed tiers and in end to end relation, means providing a cement joint between the ends of the adjacent blocks, separable sealing keys wholly covering the abutting ends of the adjacent blocks on the outer face of the wall, and means depending from the blocks of one tier and arranged in overlapping engagement with the blocks in the next lower tier and the sealing keys therefor.

2. In a wall, identically constructed building blocks disposed in superimposed tiers and in end to end relation, means providing a cement joint between the ends of the adjacent blocks, vertically disposed separable sealing keys wholly covering the abutting ends of adjacent blocks on the outer face of the wall, and a flange depending from each block and arranged in overlapping engagement with the corresponding block in the next lower tier and said covering means therefor.

3. In a wall, identically constructed building blocks disposed in superimposed tiers and in end to end relation, means providing a cement joint between the ends of adjacent blocks, separable sealing keys vertically supported by the adjacent blocks on the outer faces thereof and wholly covering the abutting ends thereof, and means depending from the blocks of one tier and arranged in overlapping engagement with the blocks and said covering means therefor in the next lower tier.

4. In a wall, building blocks disposed in superimposed tiers and arranged in end to end relation, means joining the ends of adjacent blocks, the 60

outer face of each block having tapered recesses at the ends thereof, whereby said recesses of adjacent blocks unitedly define a tapered pocket, a sealing key received by said pocket and wholly covering the abutting ends of adjacent blocks on the outer face of the wall, and a flange depending from each block in overlapping engagement with adjacent blocks of the next lower tier and bridging said sealing key.

5. In a wall, building blocks disposed in superimposed tiers and in end to end relation, means joining the ends of adjacent blocks, the outer face of each block having tapered recesses at the ends thereof, whereby said recesses of adjacent blocks unitedly define a wedge-shaped pocket opening at the upper edges of said blocks, a correspondingly shaped sealing key slidably received by said pocket and wholly covering the abutting ends of the adjacent blocks on the outer face of the wall, and a flange depending from each block in overlapping engagement with adjacent blocks of the next lower tier and the sealing key therefor.

6. In a wall, building blocks disposed in superimposed tiers and in end to end relation, means joining the ends of adjacent blocks, the outer face of each block having tapered recesses at the ends thereof, whereby said recesses of adjacent blocks unitedly define a tapered pocket opening at the upper edges of said blocks, a correspondingly shaped sealing key slidably received by said pocket and covering the abutting ends of the adjacent blocks on the outer face of the wall, each key having inclined edges effectively engaging the tapered edges of the pocket under slight pressure from the weight of the adjacent block of the next upper tier.

7. In a wall, building blocks disposed in superimposed tiers and in end to end relation, means joining the ends of adjacent blocks, the outer face of each block having tapered recesses at the ends thereof, whereby said recesses of adjacent blocks unitedly define a tapered pocket, a correspondingly shaped sealing key snugly fitted in said pocket and wholly covering the abutting ends of adjacent blocks on the outer face of the wall, and means on a vertically adjacent block to overlap the key to keep it in position.

8. In a wall, building blocks disposed in superimposed tiers and in end to end relation, means joining the ends of adjacent blocks, the outer face of each block having tapered recesses at the ends thereof, whereby said recesses of adjacent blocks unitedly define a tapered pocket, a sealing key slidably received by said pocket and wholly covering the abutting ends of adjacent blocks on the outer face of the wall, and a flange on each block engageable with the key of a pair of adjacent blocks to keep the key in position.

HENRY W. HAAKER.
